US00D913990S

(12) **United States Design Patent** (10) Patent No.: **US D913,990 S**
(45) Date of Patent: **** Mar. 23, 2021**

(54) **HEADPHONES**

(71) Applicant: **Dolby Laboratories Licensing Corporation**, San Francisco, CA (US)

(72) Inventors: **Lucas E. Saule**, San Francisco, CA (US); **Vincent Voron**, Menlo Park, CA (US); **Peter Michaelian**, San Francisco, CA (US); **Guangyu Jin**, San Francisco, CA (US); **Kevin J. Kilpatrick**, Mountain View, CA (US); **Branko Lukic**, Menlo Park, CA (US); **Steven Ryutaro Takayama**, Menlo Park, CA (US); **Grayson H. Byrd**, San Francisco, CA (US); **Adam Scott Koniak**, Redwood City, CA (US); **Ariel Laurent Fischer**, San Francisco, CA (US); **Robert Edward Borchers**, Pleasanton, CA (US)

(73) Assignee: **Dolby Laboratories Licensing Corporation**, San Francisco, CA (US)

(**) Term: **15 Years**

(21) Appl. No.: **29/714,175**

(22) Filed: **Nov. 21, 2019**

Related U.S. Application Data

(63) Continuation of application No. 29/662,004, filed on Aug. 31, 2018, now Pat. No. Des. 871,368.

(57) CLAIM

The ornamental design for headphones, as shown and described.

DESCRIPTION

FIG. 1 is a perspective view of headphones showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines illustrate structure or features which form no part of the claimed design.
